UNITED STATES PATENT OFFICE

LONZO B. SMITH, OF RICHWOOD, WEST VIRGINIA

RESYNCHRONIZER FOR DISK TALKING MACHINES

Application filed October 10, 1929. Serial No. 398,661.

My invention relates to improvements in re-synchronizers for disk talking machines, and refers particularly to a mechanism for use in the production of sound pictures and in conjunction with a projecting machine and suitable amplifier, the projecting machine and amplifier forming no part of my invention.

One object of my invention is the provision of a mechanism which will operate in perfect register of synchrony with the travel of the film to insure the most perfect synchrony of the sound and which can be instantly moved to the left when is ahead of the picture or to the right when sound is back or behind the picture, and which in the event of the record slipping on the turn table, or a section being absent from the film, can be readily and quickly moved to effect the desired re-synchronizing to insure perfect transmission of the sound and in register or synchrony with the film.

Another object of my invention is the provision of a mechanism which will operate in perfect register or synchrony with the travel of the film to insure the most satisfactory results and which can be quickly adjusted to insure re-synchronizing when necessary and which mechanism will insure a smooth and even transmission of the sound from the record to and through the amplifier to produce practical results.

Another object of my invention is the provision of a mechanism of the character and for the purpose stated which will be of simple, strong and durable construction to withstand hard and constant usage, which will be small and compact in size to occupy a small amount of space, which will be inexpensive to manufacture and which will be thoroughly efficient and practical in every respect.

With these objects in view my invention consists of a re-synchronizing mechanism embodying novel features of construction and combination of parts substantially as described and claimed and as shown in the accompanying drawing, in which:

Figure 1 represents a vertical sectional view of the complete mechanism constructed in accordance with and embodying my invention.

Figure 2 represents a top plan view of the mechanism with the turn table removed to show more clearly the construction and arrangement of the parts of my invention.

Figure 3 represents a plan view of one or the upper insulating ring or member of my machine.

Figure 4 represents a top plan view of the other or lower insulating ring or member of my invention.

Figure 5 represents a plan view and edge view of spring washer used for friction action in regulating pressure on the hub of the hand wheel.

Figure 6 represents a section taken on line 6-6 of Figure 3, showing the form of the upper insulating ring, and

Figure 7 represents a section on line 7-7 of Figure 7, showing the form of the lower insulating ring.

Referring by numeral to the drawing in which similar numerals are used to denote the same parts in all the views:

The numeral 1 designates the main casing or support which could be a part of the gear box and which is formed with the stud or boss 2, provided with an opening 3, in which is guided and adapted to rotate the shaft 4, upon which is mounted the turn table 5, which carries the record and which turn table rotates in register or synchrony with the travel of the film, and resting upon the shoulder 6, at the base of the boss is the flat insulating ring 7, which has arranged thereon the pair of flat copper or metal split rings 8 and 8', from which lead the wires 9 and 9', to the amplifier, which forms no part of my invention and is not shown.

Upon the said ring 7 is mounted the upper insulating ring 10, which is formed with the pair of annular grooves or channels 11 and 11', to fit upon and very snugly cover the pair of split rings 8 and 8', and said upper insulated ring 10, is formed with openings 12 and 12', which lead to the metal rings 8 and 8', and which openings admit the brushes 13 and 13', to bear upon said split rings 8 and 8', for forming current conducting means as will presently appear.

Fitting upon the resting flat on the upper

insulating ring is the hub 14, connected by spokes 15, with the rim 16, all forming the hand wheel which thus is mounted upon and permitted to turn on the boss 2, of the main casting or support, and on the upper flat face of said hub rests the flat washer 17, which has a key 18, fitting in a key-way 19, of the boss 2, and which retains said washer from turning but allows the hub of the hand wheel to turn when necessary by manual operation, and on said washer rests the waved spring ring 20, which is properly confined by the cap ring 21, threaded at 22, to engage the threads 23, on the boss 2, and which ring is retained in proper adjustment by the set screw 24, and which thus acts upon the friction spring ring to retain it in place and also to allow the manual turning of the hand wheel when desired.

From the hub of the hand wheel leads the arm 25, which is also connected at 26, with the rim of the hand wheel and carries the vertical mounting 27, for the rod 28, to which is pivotally connected the pick up or transmitter 29, and leading from the mounting 27, and through the arm 25, to the brushes 13 and 13', are the electric conduct wires 30 and 30', which carry the sound from the pick up, through the split rings and to the amplifier, as will be readily understood.

The operation of my invention will be readily understood by all conversant with structures of this character from the drawings and description, and it will be apparent that the sound passes from the record on the turn table, through the pick up and through the conducting wires to the amplifier in a smooth and even manner and in perfect register or synchrony with the travel of the film, and when the sound is produced ahead of the picture the turning of the hand wheel to the left brings the pick up in proper place, and also turning the hand wheel to the right brings the sound from behind or after to the picture into proper register or synchrony, and if a section of the film is absent or defective, the hand wheel can be properly moved to place the pick up in the desired groove of the record, and thus the mechanism is under manual operation and control at all times to permit the instant synchronizing of the sound on the record with the pictures on the film.

It will be apparent that my invention possesses every feature of merit to command it as useful, desirable and practical for the purposes intended.

It will be understood that the insulated rings 7 and 10 are fixed or stationary, also that the split rings will operate if made continuous, and that generally that I reserve the right to make any changes or modifications which fall within the scope of the claims of this application.

I claim:

1. In a mechanism of the character and for the purpose described, the combination with a record carrying turn table capable of rotation in one direction, of a transmitter or pick up, and a mounting for said pick up capable of manual turning to the right or left with reference to the movement of the said record carrying table said mounting comprising a hand wheel, an arm carried by said hand wheel and upon which the pick up is pivoted.

2. In a mechanism of the character and for the purpose described, the combination with a record carrying turn table, a hand wheel adapted to be turned to the right or left with reference to the rotation of said turn table, a pick up carried by and movable with said hand wheel, and electrical connections leading from said pick up through the hand wheel to an amplifier.

3. In a mechanism of the character and for the purpose described, the combination with a record carrying turn table, a hand wheel having its hub fitted around the shaft of said turn table, an arm leading from said hub, a pick up mounting connected with said arm, a pick up, a pair of insulating rings upon which the hub of the hand wheel rests, a pair of metal split rings confined between said insulating rings, a pair of brushes passing through the upper of said insulating rings and bearing upon said split metal rings, and wires leading from said brushes to the mounting of said pick up.

4. In a mechanism of the character and for the purpose described, the combination of a support formed with a boss, a shaft passing through said boss, a record carrying turn table on said shaft, a pair of insulating rings fitting upon said boss and resting on said support, a pair of split metal rings confined between said insulating rings, wires leading from said rings to an amplifier, a pair of brushes passing through one of said insulating rings and forming contact with said split metal rings, a hand wheel having a hub fitting around said boss and resting on said insulating rings, a cap ring on said boss, friction washers between the cap plate and hub of said hand wheel, an arm extending from said hub to the rim of said hand wheel, a pick up mount supported by said arm, a pick up, and wires leading from said pick up mounting to said brushes.

In testimony whereof I affix my signature.
LONZO B. SMITH.
